UNITED STATES PATENT OFFICE.

GEORGE WILLIAM SAGE, OF EAST SAINT JOHN, AND GEORGE HENRY SIMPSON, OF GLEN FALLS, CANADA.

BELT FASTENER.

Application filed October 20, 1924. Serial No. 744,858.

To all whom it may concern:

Be it known that we, GEORGE WILLIAM SAGE and GEORGE HENRY SIMPSON, citizens of the Dominion of Canada, residing at East 5 Saint John and Glen Falls, respectively, in the county of Saint John and Province of New Brunswick, Dominion of Canada, have invented certain new and useful Improvements in Belt Fasteners, of which the following is a specification.

Our invention relates to improvements in fasteners and more especially to that type of fasteners used to connect the ends of belts and the like.

15 An important object of our invention is to provide a device of the above-mentioned character which will be interlocking but which will not depend upon a straight pull to keep it coupled.

20 Another object of our invention is to provide a device of this character which will not have metal portions on the side of the belt adjacent the pulley.

25 A further object of our invention is to provide a device of this character which is capable of being constructed from very strong material.

Another object of our invention is to 30 provide a device of the above-mentioned character which may be easily and cheaply manufactured but which will be strong and durable in use.

35 Other objects and advantages of our invention will be apparent during the course of the following description.

In the accompanying drawings which 40 form a part of this specification and wherein like characters of reference denote like or correspondings parts throughout the same—

Figure 1 is a top plan view of the device applied to a belt,

Figure 2 is a similar view showing the device uncoupled,

Figure 3 is a side elevation of Figure 1,

Figure 4 is a longitudinal section showing the parts in position to be uncoupled,

Figure 5 is a side elevation, parts being in section,

Figure 6 is a perspective view showing the position of the sections before coupling or after uncoupling,

Figure 7 is a perspective view showing the device in its coupled position, and

Figure 8 is a detail section showing the arrangement of the securing rivet.

In the drawings wherein for the purpose of illustration is shown a preferred embodiment of our invention, the numeral 10 designates a belt of the usual construction having the fastening sections 11 and 12 secured to its ends by means of the split rivets 13 which are punched through the belt. This construction is such that the belt is not weakened, as is the case when holes are cut therein to receive fasteners, and none of the metal of the fastening sections comes in contact with the pulley about which the belt is arranged.

The end of the female section 11 is turned up at right angles to form the flange 14. 70 Transverse slots 15 are arranged parallel to and in spaced relation with the right angle flange 14. Longitudinal slots 16 open into the slot 15 at right angles, forming a T-shaped slot, therewith, the other end of said 75 slot 16 extending a portion of the way up the flange 14 as at 17 but terminating a substantial distance short of the top of the flange..

The male section 12 is provided with a 80 pair of T-shaped tongues comprising the transverse head portions 18 connected to the body of the section by means of the longitudinal neck portions 19 which are of a width substantially less than the width of 85 the head portions 18.

In order to couple the sections it is first necessary to arrange the section 12 at right angles to the section 11, as illustrated by Figure 6. The T-shaped tongues are then 90 inserted through the transverse slots 15 as shown in Figure 4 so that the heads 18 of the tongues are arranged above the surface of the section 11. The section 12 is then drawn towards the flange 14, the necks 19 of 95 the tongues engaging in the longitudinal slots 16, until the flange is reached, in which position the male section 12 is capable of pivoting to assume the horizontal position as shown in dotted lines in Figure 4 and in 100 full lines in Figure 5. In this position, it will be seen that the lower surface of the T-shaped tongues engage the upper surface 105 of the female section 11, and the upper surface of the T-shaped tongues engage the end 105 of the portion 17 of the slot 16. This arrangement is such that no upward movement is possible, although the section 12 is capable of pivoting downwardly as shown in dotted lines in Figure 3.

In order to uncouple the sections it is first necessary that the section 12 be arranged at an angle of 90 degrees with respect to the section 11, as clearly shown in Figures 4 and 5. In no other position is it possible for the device to be uncoupled.

It will be seen that the construction of this device is such that it may be formed from any size or thickness or material and 10 that it does not depend upon a straight pull to keep it in its coupled position, as is the case with most devices of this kind now on the market.

While we have shown and described the 15 preferred form of our invention, it is to be understood that various changes in the size, shape and arrangement of parts may be resorted to without departing from the spirit 20 of our invention or the scope of the subjoined claims.

Having described our invention, what we claim and desire to protect by Letters Patent is:

1. In a device of the character described, 25 a female section, one end of which is turned up at right angles to form a flange, said section being provided with a T-shaped slot, the longitudinal portion of which extends a substantial distance up said right angled 30 flange, a male section, and a T-shaped tongue carried thereby and adapted to be inserted in the T-shaped slot to couple the sections, the lower surface of the T-shaped tongue being adapted to contact with the upper surface of 35 the female member when coupled, and the upper surface of the tongue being adapted to engage the end of the longitudinal portion

of the T-shaped slot to prevent movement of the tongue in that direction.

2. In a device of the character described, a 40 belt, a female coupling section riveted at one end to one end of the belt in such manner that no parts of the section are arranged upon the opposite side of the belt, said section having the other of its ends turned up 45 at right angles to form a flange, said section having a pair of T-shaped slots arranged therein, the head portions of said slots being arranged parallel with and in spaced relation to the right angled flange, the longitudinal 50 portions of the slot extending up said flange but falling short a substantial distance from the top thereof, a male section riveted at one end to the opposite end of the belt in such manner that no parts of the section are arranged upon the opposite side of the belt, and a pair of T-shaped tongues carried by the other end of said male section and adapted to be inserted in the slots in the female sections when the sections are arranged 55 at right angles to each other and being incapable of removal at any other angle, the two sections being adapted to be normally arranged in a parallel plane with the tongues bearing against the surface of 60 the female section on one side and against the end of the longitudinal portion of the T-shaped slot, on the other side, whereby the sections may be pivoted in one direction but not in the other.

In testimony whereof we affix our signatures.

GEORGE WILLIAM SAGE.
GEORGE HENRY SIMPSON.
